GUN SIGHT

Harold F. Mossberg, New Haven, Conn., assignor
to O. F. Mossberg & Sons, Incorporated, New
Haven, Conn., a corporation

Application May 8, 1935, Serial No. 20,305

6 Claims. (Cl. 33—50)

This invention relates to improvements in gun-sights.

One object of this invention is to provide an improved gun-sight construction including a telescopic-sight and an ordinary rear-sight, both so mounted as to be selectively shiftable into and out of the normal line of sight without the need of detaching either sight from the gun.

Another object of this invention is to provide an improved gun-sight construction formed of simple elements readily manufactured and readily assembled to produce a durable, efficient construction at minimum cost.

With the above and other objects in view, this invention includes all improvements over the prior art which are disclosed in this application.

In the accompanying drawings, in which one way of carrying out the invention is shown for illustrative purposes:

20 Fig. 1 is a side elevation of a gun illustrating one embodiment of an improved gun-sight construction made in accordance with this invention;

25 Fig. 2 is an enlarged side elevation of a portion of Fig. 1, with the sighting elements occupying different positions from those shown in Fig. 1;

Fig. 3 is a right-end elevation of Fig. 2;

Fig. 4 is a view similar to Fig. 3, but with the sighting members moved to positions corresponding to those they occupy in Fig. 1;

30 Fig. 5 is an enlarged vertical sectional view of the rear peep-sight construction on the plane indicated by line 5—5 of Fig. 1;

Fig. 6 is a horizontal sectional view on the plane indicated by line 6—6 of Fig. 5;

35 Fig. 7 is a perspective view of the two main supporting parts of the rear peep-sight construction;

Fig. 8 is a rear perspective view of the click-spring; and

40 Fig. 9 is a horizontal sectional view on line 9—9 of Fig. 2.

In the description and claims, the various parts are identified by specific names for convenience, but they are intended to be as generic in their application as the prior art will permit.

Referring to the drawings, the receiver 20 is detachably mounted on the stock 21 of the gun and detachably receives the rear end of the barrel 22. Secured to the receiver 20 in any suitable way, as by screws 23, is a rear peep-sight base 24 having a threaded opening 25 and a coaxial, up-standing, cylindrical opening 26, in which opening 26 a stem or sight-supporting member 27 is mounted for horizontal rotation and up-and-down sliding movements. The stem 27 has a

cylindrical opening 28 which houses a coil-spring 29 under endwise compression and down through which coil-spring 29 extends a stud 30 having its lower end 31 screw-threadedly engaged in the screw-threaded opening 25. Rigidly secured to 5 or formed integral with the stem 27 is a horizontally-extending bar or shank 32 having a cylindrical opening 33 extending out through one end of the shank 32, and having opposite openings 34 and 35 extending out through opposite 10 side-walls 36 and 37 respectively.

An adjusting-pin 38 has a cylindrical head 39 slidably mounted in the cylindrical opening 33, and a reduced shank-portion 40 extending through a coil-spring 41 under endwise compression, and having its screw-threaded end 42 threadedly engaged by the adjusting-nut or knob 43.

The head 39 has a transverse screw-threaded opening 44 adapted to be threadedly engaged 20 by the screw-threaded shank 45 of a rear sight-member such as the peep-sight member 46, which latter has an annular shoulder or flange 47 adapted to abut against the outer face of the wall 36 when the shank 45 of the sight-member is engaged in the threaded opening 44.

A click-spring 48 is secured by screws 49 and 50 to the stem 27 and has a spring-arm 51 provided with a click-point or boss 52 adapted to resiliently snap into and out of the notches 53 30 in the adjusting-head 54, and also has a second spring-arm 55 provided with a click-point or boss 56 adapted to resiliently snap into and out of notches 57 of the adjusting-nut 43.

The base 24 is cut away at 58 (Fig. 7) to provide two limit-shoulders 59 and 60, which are adapted to be engaged by a limit-pin 61, rigidly secured to the bar or shank 32. The base 24 has a threaded opening 62 (Fig. 5) in which is threadedly engaged the threaded shank of a set-screw 63. A coil-spring 64 is under compression between the base 24 and the head of the set-screw 63.

The telescopic-sight construction includes a bracket 65 secured by screws 66 to the receiver 20. 45 The bracket 65 is provided with a dovetailed guide-slot construction 67 in which adjustably slides the longitudinally-split tang 68 of a telescopic sight-carrying bracket 69. A bolt 70 has a conical head 71 (Fig. 9) engaged in a conical 50 opening 72 formed midway of the split tang 68. The head 71 has secured therein a pin 73 which lies within the longitudinal slot 74 of the split tang 68 to prevent rotation of the bolt 70 relative to the tang 68. The outer threaded end 75 of the 55

bolt 70 is threadedly engaged by a lever-nut 76 which is adapted to be turned to press against the washer 77 to draw the conical head 71 against the walls of the conical opening 72 and spread 5 apart the parts of the tang 68 on opposite sides of the slot 74 so as to jam the tang 68 against the walls of the dovetailed slot 67, to thus lock the tang in any desired vertically-adjusted position. The telescopic-sight-carrying bracket 69 10 carries the telescopic-sight 78 therein for angular adjustment both vertically and horizontally 15 in a manner well-known in the art.

For ordinary shooting, where the rear peep-sight 46 is to be used, the lever-nut 76 is loosened 15 and the telescopic-sight-carrying bracket 69, with its telescope 78, is raised from the position shown in Figs. 1 and 4 to that shown in Figs. 2 and 3, whereupon the lever-nut is again tightened 20 to hold the bracket 69 and tang 68 in the elevated position. Then, the set-screw 63 is loosened and the sleeve 27 is rotated in a horizontal plane to swing the peep-sight member 46 from the position shown in Figs. 1 and 4, and in solid lines in Fig. 6, to the position shown in 25 Figs. 2 and 3, and in dotted lines in Fig. 6, thus causing the limit-pin 61 to move away from the limit-shoulder 59 (Fig. 7) and engage against the limit-shoulder 60, whereupon the set-screw 63 is tightened 30 to hold the rear peep-sight in adjusted position for sighting.

If the sight is to be adjusted for elevation, the set-screw 63 is loosened and the adjusting-head 54 is rotated in one direction or the other until the click-spring 48 snaps past the desired number 35 of notches 53 to correspondingly raise the bolt 30 and result in the stem 27 being raised by the spring 29, or lower the bolt 30 and force the stem down against the action of the spring 39, whereupon the set-screw 63 is again tightened. 40 If adjustment is to be made for windage, the adjusting-nut 43 is rotated in one direction or the other to cause the bolt 38, together with the peep-sight 46 carried thereby, to be correspondingly adjusted in one direction or the other, depending 45 upon the direction of the wind.

If it is then desired to use the telescopic sight instead of the rear peep-sight, the set-screw 63 is loosened and the stem 27 is rotated from the position shown in Figs. 2 and 3, and in dotted 50 lines in Fig. 6, to that shown in Figs. 1 and 4, and in solid lines in Fig. 6, thus moving the peep-sight out of and sufficiently away from the line of sight to permit the telescopic-sight-carrying bracket 69 and its telescopic-sight 78 to be moved 55 down to bring the telescopic-sight close to the gun-receiver or barrel of the gun and substantially in the normal line of sight of the gun.

The invention may be carried out in other specific ways than that herein set forth without departing from the spirit and essential characteristics of the invention, and the present embodiment is therefore to be considered in all respects as illustrative and not restrictive, and all changes coming within the meaning and equivalency 65 range of the appended claims are intended to be embraced therein.

I claim:

1. A gun-sight construction including: a guide-bracket; a telescopic-sight carrying bracket having means engaging and supporting said telescopic-sight at two locations widely spaced apart longitudinally of the telescopic-sight, and having means for angularly adjusting the telescopic-sight 70

sight relatively to said bracket; said carrying bracket having a depending tang permanently rigid therewith and adapted to slidably engage said guide-bracket and adapted to be rigidly secured thereto in various positions of vertical adjustment. 5

2. A gun-sight construction including: a guide-bracket; a telescopic-sight carrying bracket having means engaging and supporting said telescopic-sight at two locations widely spaced apart longitudinally 10 of the telescopic-sight, and having means for angularly adjusting the telescopic sight relatively to said bracket; said carrying bracket having a depending tang permanently rigid therewith approximately midway of its length 15 and adapted to slidably engage said guide-bracket and adapted to be rigidly secured thereto in various positions of vertical adjustment.

3. A gun-sight construction including: a guide-bracket having vertically-extending guide-means; a telescopic-sight carrying bracket having means engaging and supporting said telescopic-sight at two locations widely spaced apart longitudinally 20 of the telescopic-sight, and having means for angularly adjusting the telescopic sight relatively to 25 said bracket; said carrying bracket having depending guide-means permanently rigid therewith and approximately midway of its length and adapted to slidably engage said guide-bracket guide-means, and one of said guide-means adapted 30 to be distorted to rigidly secure it to the other guide-means in various positions of vertical adjustment.

4. A gun-sight construction including: a guide-bracket having a vertically-extending guide-slot; a telescopic-sight carrying bracket having means engaging and supporting said telescopic-sight at two locations widely spaced apart longitudinally 35 of the telescopic-sight, and having means for angularly adjusting the telescopic sight relatively to 40 said bracket; said carrying bracket having a depending tang permanently rigid therewith and adapted to slidably engage in said guide-slot and adapted to be rigidly secured therein in various 45 positions of vertical adjustment.

5. A gun-sight construction including: a guide-bracket having a vertically-extending guide-slot; a telescopic-sight carrying bracket having means engaging and supporting said telescopic-sight at two locations widely spaced apart longitudinally 50 of the telescopic-sight, and having means for angularly adjusting the telescopic sight relatively to 55 said bracket; said carrying bracket having a depending tang permanently rigid therewith and approximately midway of its length and adapted to be expanded to be rigidly secured therein in various positions of vertical adjustment.

6. A gun-sight construction including: a guide-bracket having a vertically-extending guide-slot; a telescopic-sight carrying bracket having means engaging and supporting said telescopic-sight at two locations widely spaced apart longitudinally 60 of the telescopic-sight, and having means for angularly adjusting the telescopic sight relatively 65 to said bracket; said carrying bracket having a depending split-tang permanently rigid therewith and adapted to slidably engage in said guide-slot and the split portions of said tang being adapted to be spread apart to rigidly secure the 70 tang in said guide-slot in various positions of vertical adjustment.

HAROLD F. MOSSBERG.
